DANIEL GORDON EDWARDS, OF HOPKINSVILLE, KENTUCKY.

AIR PUMP.

1,405,907.

Specification of Letters Patent.

Patented Feb. 7, 1922.

Application filed January 19, 1920. Serial No. 352,297.

To all whom it may concern:

Be it known that I, DANIEL GORDON EDWARDS, a citizen of the United States, residing at Hopkinsville, in the county of Christian and State of Kentucky, have invented certain new and useful Improvements in Air Pumps, of which the following is a specification.

This invention relates to air pumps, and 10 more particularly to pumps employed for the inflation of pneumatic tires, and the like.

While especially useful in connection with manually operated air compressors of the type commonly known as foot pumps, which 15 type I have shown in the drawings, by way of illustration, it will be understood that my improvements are not limited to such use, as the invention, in its broader aspects, is equally applicable to other types of 20 pumps, either compression or vacuum.

In reciprocating air pumps as ordinarily constructed, the piston comprises a flexible, cup shaped member, usually of leather, intended to make a substantially air-tight fit 25 within the barrel or cylinder, fluid pressure being relied upon to force the edges of such cup leather against the walls of the cylinder to prevent leakage past the same. It has been found in practice, however, that the leather 30 cup, through lack of proper lubrication and other causes, frequently becomes stiff and more or less rigid, and this, together with reduction in the diameter of the cup, due to wear or shrinkage, results in the free escape 35 of air past the piston, and makes it impossible to produce a high compression or vacuum.

It has heretofore been proposed to press the edges of the leather cup into contact with 40 the cylinder walls by means of an expander block or the like urged by a spring, but in such an arrangement the spring pressure is constant, being effective during the idle stroke as well as the working stroke, and this 45 continual pressure serves to wear away the leather very rapidly.

It is the primary object of the present invention to provide positive mechanical means for expanding the cup leather into 50 close contact with the cylinder walls during the working stroke, and to permit the same to retract during the idle stroke, whereby high compression is secured, and wear reduced to a minimum. In carrying out this 55 object, I propose a construction in which the expanding force increases in direct propor-

tion to the load or resistance encountered by the piston, so that the higher the compression the tighter the fit of the cup leather within the barrel. In this way, leakage at 60 any and all loads is effectively prevented.

A further object is to combine the expander feature above described, with a positive, mechanically actuated valve for admitting air into the cylinder through the piston, 65 during its idle or return stroke.

With the above objects in view, and to improve generally on the structural details of such apparatus with a view to increasing its efficiency, the invention consists in the 70 construction, combination and arrangement of parts hereinafter described and claimed, and illustrated in the accompanying drawing, in which:—

Fig. 1 is a longitudinal section through a 75 foot pump embodying my improvements;

Fig. 2 is an end elevation of the operating handle, the piston rod being in section;

Fig. 3 is an end view of a cup shaped 80 spring which I employ;

Fig. 4 is a side view thereof;

Fig. 5 is a side view of a resilient metallic cup, which I employ inside of the usual flexible cup;

Figs. 6 and 7 are fragmentary longitudinal sections similar to Fig. 1, but showing modified constructions, and 85

Fig. 8 is a sectional view of the operating handle similar to Fig. 1, but showing a slightly modified arrangement. 90

Referring to the drawings in detail, and more particularly to Figs. 1 and 2 thereof, my improved pump comprises the usual cylinder or barrel 1, which in practice is preferably formed of brass tubing. This barrel is 95 screwed into a base or pedestal 2, carrying the usual loop or stirrup 3, into which the operator's foot is inserted. In order to prevent the pump from slipping, I preferably provide one or more spurs 4 on the under side of the stirrup, such spurs serving 100 to engage the surface on which the stirrup rests.

In the base 2 is formed a recess 5 for a purpose hereinafter described and from this 105 recess extends the delivery port with which the usual elbow 6, preferably carrying a check valve, connects. For the purpose of tire inflation, a flexible hose 8 is attached to the elbow 6, by means of a coupling 7, the 110 end of the coupling inserted in the hose preferably being threaded as indicated at

7^a, and the hose, adjacent such threaded portion, being surrounded by a suitable clamp 9.

Working within the cylinder or barrel 1 5 is a piston carried by a piston rod 10, which rod consists of a small piece of pipe or tubing, as shown. The end of the barrel opposite to the base is closed by a cap or cover 11 preferably having air holes 12 there- 10 through.

The piston comprises a rigid plate or disc 13 screw threaded onto the piston rod 10 and a superposed disc 14 of soft absorbent material, such as felt. A washer 15 secures 15 the felt disc in position. This felt disc is for the purpose of absorbing a suitable lubricant, and thus keeping the piston in working order.

Adjacent the rigid disc 13 is the usual 20 flexible cup 17 preferably formed of leather or the like, and inside of this flexible cup is a metallic cup 18 having resilient side walls, preferably slit as shown in Fig. 5 to permit expansion. It will be noted that 25 the flexible cup 17 is held between the resilient cup 18 and the rigid disc 13 and that such rigid disc is mounted between the flexible cup and absorbent washer 14.

Secured to the extreme end of the piston 30 rod 10 inside of the resilient cup 18 is a valve seat 27, preferably formed of rubber or the like, and co-operating with this valve seat, is a valve 28.

Fitting within the resilient cup 18 and 35 versely disposed in respect thereto is a cup shaped spring 19, clearly shown in Figs. 3 and 4. This comprises a marginal portion provided with slits 19^a, which slits extend radially inward towards the center and with 40 a raised central portion 19^b having an opening therethrough. This opening fits over the end of a pull rod 21, which extends down through the hollow piston rod 10, and the spring member 19 is secured on 45 the screw-threaded end of such rod, by means of lock nuts 20. The valve 28 is mounted on the rod 21 within the hollow of the cup shaped spring 19, and is also provided with a lock nut. It will be understood that the position of the parts 19 and 50 28 relative to each other and to the metallic cup and valve seat can be adjusted as desired.

Rigidly secured to the outer end of piston rod 10 is a transversely extending operating handle 22, held in position by means of a nut 23. A spring 10^a is interposed between this handle and the cap 11 to cushion the movement of the piston, and prevent 60 hammering thereof against the base 2.

Pivoted to the handle 22 as at 26 is a lever 25 shown in Fig. 1 as being similar to the handle 22. Instead of this construction, however, the operating handle may be 65 symmetrical with respect to the rod 10, as

indicated at 32 in Fig. 8, and an operating lever such as 35 may be pivoted at 36 to such handle, a spring 33 being in this case preferably interposed between the handle and lever and tending to move the lever 70 in one direction.

The outer end of the pull rod or valve rod 21 is pivotally connected at 24 to the handle lever 25 shown in Fig. 1, or to the lever 35 shown in Fig. 8, as the case may be. 75

Whichever construction is employed, it will be apparent that when the handle is grasped by the operator, and pressure applied in such a direction as to produce a working stroke of the piston, the lever 25 80 or 35 will first be given an initial pivotal movement, relative to the handle, and this initial pivotal movement exerts a pull upon the rod 21. This pull simultaneously produces two results, first, it closes the valve 85 28 against its seat 27, and, second, it exerts pressure against the convex middle portion of the cup shaped springs 19, thus causing such spring to expand radially, thereby expanding the cups 17 and 18 and forcing the 90 former into intimate contact with the walls of the cylinder. The continued application of force to the operating handle in the same direction produces the working stroke of the piston, thus driving out the air contained 95 between itself and the base 2. The recess 5 in the base 2 is adapted to receive the lock nuts 20 and convex portion 19^b of the cup shaped springs 19, thus permitting the working portion of the piston to approach 100 the base 2 very closely. This reduces the necessary clearance to a minimum and enables the pump to work very efficiently.

On the return or idle stroke of the piston, the lever 25 partakes of an initial pivotal 105 movement in the other direction, thus opening the valve 28 and relieving the pressure on the cup shaped spring 19. This permits the resilient and flexible cups to contract and also allows air to pass freely down through 110 the openings 12 and thence through openings 16 formed in the hollow piston rod 10 through the valve 28 into the barrel of the pump. It will be noted that the outer end of the hollow piston rod 10 is also open, so 115 that air may enter through this channel as well.

Instead of employing the cup shaped spring shown in Fig. 1, I may use a solid or non-resilient spreader as shown in Fig. 120 6. Referring to this figure, it will be seen that I mount a conical or tapered block or plug 29 on the end of the pull rod 21, a tapering surface of this block engaging the edges of the resilient cup 18, and this expands the same as the flexible cup 17. In this connection it may be stated that the purpose of the resilient cup 18 in both of these modifications is to hold the flexible cup and prevent it from wrinkling or bu- 125 130

kling, as might be the case if the spreader directly engaged such flexible cup.

In Fig. 7 I have shown still further modification in which, instead of the tapering block 29, I employ a flat rigid disk 39 preferably having openings therethrough. This disc, itself, serves as a valve to engage the valve seat 37 and its outer edges are preferably rounded or bevelled. These rounded edges engage a conical portion 38^a of a special form of resilient cup 38, and thus expands such cup as the disc 39 is moved axially into valve closing position. In this case a reinforcing washer 30 is used to support the flexible cup 17', which is necessarily somewhat longer than in the modifications.

It will be seen that in all of the three forms of the invention illustrated in the drawings, I have provided means operated by the initial force applied to the handle for expanding the flexible cup into intimate contact with the walls of the cylinder during the working stroke of the pistons, and for simultaneously closing the valve, and it is thought that the many advantages of my improved construction will be apparent without further discussion.

What I claim is:

1. In an air pump, the combination with a cylinder and piston, of positively acting mechanical means for causing the piston to expand so as to fit the cylinder tightly during the working stroke, and permitting it to contract so as to slide freely therein during the idle or return stroke.

2. In an air pump, the combination with a cylinder, and a piston working in the same, and comprising a flexible cup, of mechanical means for expanding the sides of said cup into contact with the cylinder walls with a force always proportional to the load or resistance against which the piston is working.

3. In an air pump, the combination with a cylinder, and a piston working in the same, and comprising a flexible cup, of mechanical means for expanding the sides of said cup into contact with the cylinder walls during the working stroke and permitting the retraction of said cup during the idle or return stroke.

4. In an air pump, the combination with a cylinder and piston, said piston comprising a flexible cup, of a hollow piston rod to which said piston is secured, and means extending through said hollow rod for expanding said cup into close contact with the cylinder walls during the working stroke of the piston, and permitting the retraction of said cup during the return stroke.

5. In an air pump, the combination with a cylinder and piston, said piston comprising a flexible cup, of a hollow piston rod to which said piston is secured, a handle secured to the outer end of said rod, a lever pivoted to said handle, and means extending

through said rod and connected with said lever for expanding said cup into close contact with the cylinder walls.

6. In an air pump, the combination with a cylinder and piston, said piston comprising a flexible cup, a piston rod, a transversely disposed handle rigidly secured to said rod, a lever pivoted to said handle, and means operated by said lever during the working stroke of the pump for expanding the said cup into close contact with the cylinder walls.

7. In an air pump, the combination with a cylinder and piston, said piston comprising a flexible cup, a piston rod, a lever extending transversely of said rod and adapted to be grasped by the hand when the pump is operated, and means actuated by said lever for expanding the said cup into close contact with the cylinder walls when force is applied to said lever in a direction to produce a working stroke of the piston.

8. In an air pump, the combination with a cylinder and piston, said piston comprising a flexible cup, a piston rod, an operating handle extending transversely of the said rod and comprising a portion capable of an initial movement independent of said rod, and means actuated by such initial movement of said portion for expanding said cup into contact with the walls of the cylinder.

9. In an air pump, the combination with a cylinder, and piston, said piston comprising a flexible cup, of a piston rod, a valve in said piston, a transverse handle secured to said rod, a lever pivoted to said handle, and means actuated by said lever for expanding said cup and simultaneously closing said valve.

10. In an air pump, the combination with a cylinder and piston, said piston comprising a flexible cup, of a valve in said piston, and mechanical means for positively expanding said cup and simultaneously closing said valve during the working stroke of the piston.

11. In an air pump, the combination with a cylinder and piston, said piston comprising a flexible cup, of a spreader located within said cup, and means for applying force to said spreader axially of the pump cylinder during the working stroke only of the piston so as to cause it to expand said cup into close contact with the walls of the cylinder.

12. In an air pump, the combination with a cylinder and piston, said piston comprising a flexible cup, of a spreader located within said cup, said spreader comprising a cup-shaped resilient member, and means for applying pressure axially to the center of such member so as to cause it to expand radially, and thus force said cup into close contact with the walls of the cylinder.

13. In an air pump, the combination with

a cylinder and piston, said piston comprising a flexible cup, of a resilient metallic cup fitting within said flexible cup, and means operating inside of said metallic cup for expanding both cups during the working of the piston.

14. In an air pump, the combination with a cylinder and piston, said piston comprising a flexible cup, of a resilient metallic cup fitting within said flexible cup, a spreader operating inside of said metallic cup, and means for applying force axially of the cylinder to said spreader to cause it to expand both cups.

15. 15. In an air pump, the combination with a cylinder and piston, said piston comprising a flexible cup, of a resilient metallic cup fitting within said flexible cup, a spreader located inside of said metallic cup and comprising a cup-shaped spring disposed reversely with respect to said metallic cup, means for compressing said spring axially so as to cause it to expand radially, and thus force the flexible cup into close contact with the cylinder walls.

16. In an air pump, the combination with a cylinder and piston, said piston comprising

ing a resilient cup, of a hollow piston rod to which said piston is secured, a valve seat formed at the end of said rod, a valve for said seat, a valve rod extending through said hollow piston rod, and movable axially thereof, and a spreader located within said flexible cup and mounted on said valve rod.

17. In a pump, the combination with a cylinder and piston, of mechanical means, movable in a direction opposite to that of the piston, for positively causing the piston to expand so as to fit the cylinder tightly during the working stroke, and permitting it to contract so as to slide freely therein during the return stroke.

18. In a pump, the combination with a cylinder and piston, of actuating means for the piston, and mechanical means for expanding the piston into close contact with the cylinder walls during the working stroke, said expanding means comprising an element connected with the actuating means, and shiftable in a direction opposite to that of the piston travel by the initial movement of said actuating means.

In testimony whereof I affix my signature.
DANIEL GORDON EDWARDS.
